CHECK MECHANISM

Ernest Davis, Syracuse, N. Y., assignor to The Prosperity Company, Inc., Syracuse, N. Y., a corporation of New York

Application July 23, 1937, Serial No. 155,289

8 Claims. (Cl. 267—8)

This invention relates to hydraulic checks or check mechanisms, and has for its object a check mechanism including a valve or valves for controlling the transfer of hydraulic liquid from one side of the piston or plunger to the other, during the movement of the piston or plunger, which valve or valves are separate from the piston or plunger and are supported by the casing in contradistinction to being carried by the plunger or piston, and which are readily adjustable and also readily removable from the outside of the casing without disturbing the plungers or parts within the casing.

It further has for its object a check mechanism in the valve which controls the flow of liquid from one side to the other of the piston and is floatingly mounted so as to be self-aligning. It also more specifically has for its object a check mechanism including a tapered pin or its equivalent carried by the casing in contradistinction to the piston and entering a passage in the piston, which pin is formed with a check valve controlled passage therethrough and also such pin being mounted to have a self-aligning movement in the passage.

It further has for its object a check mechanism including oppositely movable, or alternately actuated, pistons or plungers and a reversely movable actuator coacting with the plungers alternately by a lost motion, so that there is a lost motion period, when the actuator is moving retrogradely away from one plunger toward and into engagement with the other plunger.

It further has for its object a particularly simple and economical construction of check mechanism and the casing thereof to provide a reservoir for the hydraulic liquid, with the actuator mounted outside of the reservoir and the liquid and extending into the liquid, so that liability of the liquid working its way out of the casing is entirely eliminated.

The invention consists in the novel features and in the combinations and constructions hereinafter set forth and claimed.

In describing this invention, reference is had to the accompanying drawing in which like characters designate corresponding parts in all the views.

Figure 1 is a longitudinal sectional view of a checking mechanism embodying this invention.

Figure 2 is a sectional view taken approximately on the line of 2—2, Figure 1.

Figure 3 is an enlarged fragmentary sectional view of one of the members or "pins" of the check mechanism.

This check device comprises, generally, a casing formed with a reservoir for a hydraulic liquid and one or more piston or plunger chambers communicating with the reservoir, pistons or plungers working in said chambers respectively, the structure being formed with a transfer passage or by-pass from one side of the piston or plunger, or of each piston or plunger, to the other side, valve means for controlling said transfer passage or by-pass, carried by the casing, and being removable and replaceable from the outside of the casing; or valve mechanism removable from the outside of the casing entirely independent of the movable parts, as the pistons or plungers, and an actuator coacting with the piston or plunger or pistons or plungers.

1 designates, generally, the casing formed with a portion 2 serving as an oil reservoir or a reservoir for a hydraulic liquid. 3 and 4 designate respectively piston or plunger chambers communicating with the reservoir. The casing in the illustrated embodiment of my invention is in the general form of a conduit with a tower 5 extending upwardly from the intermediate portion thereof, the end portions of the conduit forming the piston chambers 3, 4, and the intermediate portion and also the lower portion of the tower forming the oil reservoir. The piston chambers 3, 4 are thus located in opposite portions of the casing and are below the level L of the hydraulic liquid. These chambers are open at their outer ends, and their outer ends are closed by closures or caps 6, 7, here shown as threading on the ends of the tubular conduit portions of the casing confining the piston or plunger chambers 3, 4.

8 and 9 are the plungers or pistons, or other movable elements, reversely movable in the chambers 3, 4 respectively.

10 and 11 designate transfer passages from one end to the other of the pistons or plungers 8, 9, these transfer passages being preferably, and here shown as, formed entirely in the pistons or plungers, and also preferably extending axially of the pistons or plungers. These transfer passages 10, 11 are here shown as formed with branches 12, 13 opening through the opposing ends of the pistons into the reservoir. The transfer passages are controlled by valve means separate from the pistons or plungers and carried by the casing, or removable from the outside of the casing. The valve means are carried by the removable caps 6, 7 and each includes a member, as a pin or rod 14 or 15 threading through the cap 6 or 7 from the outer side thereof and ex-

tending into the passage 10 or 11. It is formed of such shape, as for instance, tapered, so as to progressively close the passage 10 or 11, and hence progressively retard the movement of the 5 plunger or piston 8, 9 in one direction, and hence effect uniform progressive checking in accordance with the speed of the piston or plunger. This is in effect a throttling means dependent for its throttling or checking effect on the speed of 10 the piston.

The valve means further includes a check valve, as a spring-pressed ball 16 in a transfer passage or by-pass 17 in each of the members 14 or 15, each passage 17 extending through the inner 15 end of each member 14 and having branches 18 opening into the piston or plunger chambers 3, 4 near the heads or caps 6, 7. The valve or ball 16 coacts with a seat 19 removably mounted or threading into the member 14 at the inner end 20 of the passage 17. The member 14 or 15 is readily adjusted axially of the pistons or plungers 8, 9 or the caps 6, 7 and is also readily removable for repairing or replacing the check valve 16. Also, the pistons or plungers 8, 9 are readily assembled 25 in the casing and readily removable and replaceable by reason of the caps 6, 7. Thus, the valves or valve means, which are generally the source of trouble in checking devices, are readily accessible without disturbing the internal parts 30 of the checking mechanism, as the pistons or plungers.

The member 14 or 15 is here shown as mounted in a passage 20 formed in a threaded gland or elongated nut 21 which threads into the cap 35 7, the pin or member 14 or 15 having a head 22 located at the bottom of a countersink 23 opening through the outer end of the nut 21. A plug 24 threads into the countersink against the head 22. A lock nut 25 holds the nut 21 40 in its axially adjusted position, and hence holds the pin 14 in its axially adjusted position. In order that the pin 14 or 15 may have a self-aligning action relative to the passage 10 or 11, the pin is mounted to shift radially, and as here 45 shown, the passage 20 in the nut 21 is of slightly larger diameter than the pin 14 or 15 to provide a clearance around the pin, and the countersink 23 is also of sufficiently large diameter to provide a clearance around the head 22 to 50 permit it to shift radially, and align the pin 14 or 15, if its tapered end or tapered side should engage the wall of the passage 10 or 11 in the piston, during the movement of the piston. A suitable spring or spring washer 26 is interposed 55 between the plug 24 and the head 22.

The actuating mechanism includes a reversely movable actuator 28, here shown as an arm, suitably mounted on a rock shaft 29 journalled in bearings in the tower 5 outside of the oil in 60 the reservoir or casing, the normal level of which is indicated by the line L. The actuator arm 28 extends into the reservoir between the opposing ends of the pistons 8, 9 and acts to alternately press against the inner end faces of the pistons 65 or plungers 8, 9. The space between the pistons or plungers 8, 9 is of considerably greater width than the actuator arm, to provide a lost-motion while the actuator arm is traveling retrogradely away from one piston toward and into engagement with the other. The inward or retrograde movement of each piston is limited by shoulders 70 2^a so that either piston can not follow up the actuator arm 28 while it is actuating the other piston, and there is the lost motion referred to 75 between the pistons and the actuator arm. The

actuator arm actuates each plunger or piston 8, 9 in one direction against the action of a returning spring 30 or 31 thrusting at one end against the cap 6 or 7 and at its other end against the piston 8 or 9, the piston 8 or 9 being provided with an annular channel for receiving the spring. The shaft 29 is intended to be connected to some part of the machine or apparatus, which has a back and forth or reverse movement, as for instance, to the movable part of a garment 10 pressing machine in which a head moves toward and from a buck, and for the purpose of connecting the shaft 29 to a mechanism to be checked in its movement, the shaft 29 is provided with an arm 32 mounted thereon outside 15 of the casing 1 or the tower 5 thereof, which may be connected to any motion transmitting part, as a link 33. The upper end of the tower 5 is closed by a removable closure 34.

In operation, after the oil has been filled into 20 the casing or reservoir through the filler hole normally closed by a plug 35, the members 14 or 15 are adjusted independently of each other to produce an equal or differential checking effect. For instance, a machine having an opening and closing movement might require checking movement during closing different from during opening. During the movement of the actuator arm 28 in one direction, as say, to the left (Figure 1), it presses against the piston or 30 plunger 8, moving it to the left into the position shown in Figure 1. During this movement, the oil passes from the left hand side of the piston or plunger 8 through the transfer passage 10 and branches 12 thereof to the inner or left 35 hand side, and the flow thereof is gradually or progressively retarded in accordance with the speed of the piston, due to the taper of the member 14. This member 14 may be adjusted axially to adjust the retarding effect to the particular conditions or installation. During this 40 movement of the actuator arm 28, the piston 9 is being moved to the left by its spring 31, the oil passing its check valve 16 through the passage 17 and branches 18 thereof. During movement of the actuator arm 28 in the other direction, or to the right, the oil then passes the check valve 16 and through the passage 17 and branches 18 thereof, while the piston or plunger 8 is being moved to the right by its spring 23. 50 Due to the lost-motion or spacing between the pistons 8, 9, the actuator arm 28 moves with no checking effect, until the lost-motion is taken up and it presses against the inner head of the piston or plunger 8 or 9, so that at the start of 55 the opening or closing or analogous movement of an apparatus, to which the checking device is connected, there is no checking effect while static inertia is being overcome.

What I claim is:

1. A check mechanism comprising a casing formed with a reservoir and a plunger chamber communicating with the reservoir, a plunger movable in the chamber and having a transfer passage opening through its opposite ends, 65 means for controlling the flow of liquid through said passage during the movement of the plunger including a member adjustably mounted in the casing and operable from the outside thereof, said member extending into the transfer passage and shaped exteriorly to progressively close the passage through the movement of the plunger as the plunger moves in one direction, and means for actuating the plunger in reverse directions. 70 75

2. A check mechanism comprising a casing formed with a reservoir and a piston chamber communicating with the reservoir, a piston movable in the chamber and formed with a transfer passage opening through its opposite ends, valve means separate from the piston for controlling the flow of liquid through the passage during the movement of the piston, said valve means being supported by the casing and operable from the outside of the casing to shift said valve means and vary the control by the valve means of fluid passing through the transfer passage, a reversely movable actuator carried by the casing and mounted outside of the reservoir and extending thereto and thrusting, when actuated, in one direction against the piston, and a spring for moving the piston in the opposite direction.

3. A check mechanism comprising a casing formed with a reservoir, and a plunger chamber communicating with the reservoir, a plunger movable in the chamber and having a transfer passage opening through its opposite ends, means for controlling the flow of liquid through the passage during the movement of the plunger comprising a member separate from the plunger and removably mounted in the casing and extending into the passage and adjustable longitudinally and shaped exteriorly to progressively restrict the transfer passage through the movement of the plunger in one direction, said member being also formed with a by-pass therethrough for transferring the liquid from one side to the other of the plunger, and a check valve in said by-pass, all whereby said member and the check valve are removable and replaceable, as a unit, from the outside of the reservoir, and means for actuating the plunger.

4. A check mechanism comprising a casing formed with a reservoir, and spaced apart plunger chambers in opposite portions of the casing, plungers movable in said chambers, the chambers and plungers being formed to provide transfer passages from one side of each of the plungers to the other side during the actuation thereof, an actuator extending between the plungers and coacting alternately with the same to actuate each plunger in one direction independently of the other, and a spring for returning each plunger in the opposite direction, the casing being provided with internal shoulders for limiting the inward movement of the plungers toward each other, whereby said plungers are spaced apart a sufficient distance to provide a lost motion between the actuator and the plungers, when the actuator is retrogradely moved out of engagement with one plunger toward the other plunger.

5. A check mechanism comprising a casing formed with a reservoir, and plunger chambers in opposite portions of the casing communicating with the reservoir and opening through outer walls of the casing, the casing having removable closures for the open outer ends of the chambers, plungers movable in said chambers respectively, each plunger being provided with a transfer passage opening through its opposite ends, members carried by said closures, having an adjusting movement axially of the closures

from the outer sides thereof and extending into the passages and shaped exteriorly to progressively restrict said passages through the movement of the plungers in one direction to control the flow of liquid therethrough during the movement of the plungers, said members having passages therein serving to transfer the liquid from one side of each plunger to the other, a check valve in each of the last passages, and a reversely movable actuator coacting with the plungers.

6. A check mechanism comprising a casing formed with a reservoir, and plunger chambers in opposite portions of the casing communicating with the reservoir and opening through outer walls of the casing, the casing having removable closures for the open outer ends of the chambers, plungers movable in said chambers respectively, each plunger being provided with a transfer passage opening through its opposite ends, members carried by said closures and extending into the passages to control the flow of liquid therethrough during the movement of the plungers, said members being separate from the plungers and having passages therein serving to transfer the liquid from one side of each plunger to the other, a check valve in each of the last passages, a reversely movable actuator coacting with the plungers, the reversely movable actuator being mounted in the casing outside the reservoir and extending into the reservoir in position to thrust alternately against the inner ends of the plungers, and springs for moving the plungers in the opposite direction, the casing being provided with shoulders for limiting the inward movement of the plungers toward each other, thereby providing a space between the plungers of greater width than the actuator, to provide a lost motion between the actuator and each plunger, when moved out of engagement with one plunger and toward and into engagement with the other.

7. A check mechanism comprising a casing formed with a reservoir, a plunger chamber communicating with the reservoir, a plunger movable in the chamber and having a transfer passage opening through its opposite ends, means for controlling the flow of liquid through the passage during the movement of the plunger comprising a throttling pin carried by the casing and separate from the plunger, the pin extending into the passage and mounted to have a self-aligning shifting movement in the passage.

8. A check mechanism comprising a casing formed with a reservoir, and a plunger chamber communicating with the reservoir, a plunger movable in the chamber and having a transfer passage opening through its opposite ends, means for controlling the flow of liquid through the passage during the movement of the plunger comprising a throttling pin carried by the casing and separate from the plunger, the pin extending into the passage and mounted to have a self-aligning radial shifting movement in the passage.
